UNITED STATES PATENT OFFICE

NOEL DEISCH, OF WASHINGTON, DISTRICT OF COLUMBIA

CONDENSER

Application filed August 20, 1930. Serial No. 476,641.

The invention relates to certain improvements in variable plate condensers and has for its object to provide such condensers, when employed as single units or in gang arrangement, with means for effecting compensating capacity adjustment, said means, broadly considered, being associated and movable with the rotor element or elements to effect limited movements of the stator element or elements relatively to the rotor or rotors and, in its more specific application, including manually actuated means for effecting the movements of the stator relatively to the rotor elements to make the compensating capacity adjustments initially, said means being associated with mechanism that is set or adjusted by the operation of said manual means to effect the subsequent capacity adjustments automatically, when the rotor elements are actuated for a given dial setting.

The invention is illustrated in the accompanying drawings, in which:—

Fig. 1 is a front elevation, partly in section, of a three gang condenser involving the novel structural and operative principles.

Fig. 2 is a rear elevation with part of the casing broken away.

Fig. 3 is a section on line 3—3 of Fig. 1.

Fig. 4 is a section on line 4—4 of Fig. 1.

Fig. 5 is a plan view of the condenser, portions thereof being shown in fragmental section.

Fig. 6 is a fragmentary front elevation of one of the disks or face plates and the associated cam with the means for mounting the letter.

Fig. 7 is a rear elevation of the mechanism shown in Fig. 6.

Fig. 8 is a fragmentary section through the face plate, illustrating the construction and arrangement of the cam and one of the runners.

Fig. 9 is a similar view showing the form of the end runners to prevent movement of the cam in a direction normal to the face plate.

Fig. 10 is a similar view showing the intermediate runner and the mode of locking

the same to the cam to prevent movement of the cam in the direction of its length.

Figs. 11 and 12 are fragmentary elevations illustrating the mode of attaching the shaft bearings to the casing.

Fig. 13 is a front elevation of a cabinet carrying an installation of a three gang condenser made in accordance with the present invention.

Fig. 14 is a fragmentary front elevation of the cabinet showing a slightly modified form in which the correcting levers are normally concealed behind a hinged door.

Fig. 15 is a circuit diagram showing the manner in which a gang condenser involving the invention is connected in a typical multi-stage receiving circuit.

Certain tuning condensers, as now made, are provided with means for securing a capacity adjustment to compensate differences of impedance with the various sub-circuits of a multi-tuned circuit at different dial settings, but these adjustments must, however,

be made by the manufacturer or by skilled service operatives provided with special equipment therefor. A factory made adjustment is frequently subject to disarrangement as the result of rough handling in shipment. Furthermore, the characteristics of the particular receiving aerial used by the set, as installed, will determine, in a large measure, the impedance of the aerial-ground sub-circuit and it will be apparent that this factor cannot be taken care of adequately at the factory. In addition to these facts and conditions which render factory adjustments unsatisfactory, the impedances of the several sub-circuits may be changed subsequent to installation, due to a substitution made in some element in the circuit, such as the receiving antenna or one or more thermionic tubes.

As shown, the present invention makes it possible for an unskilled operator of a radio receiving set to make the compensating capacity adjustments at any time the latter may be found necessary, so that he may be assured that his set is always working at its highest efficiency.

In the accompanying drawings, the invention, in its preferred form, is illustrated

as applied to a three gang condenser, such as commonly employed in radio receiving sets, but it will be understood that the invention is applicable to a single condenser or to any desired number of associated condensers.

Referring to the drawings, 1 indicates the usual housing or casing now employed as a shield for the condenser or condensers, on the ends of which casing there are mounted plates 4 and 6 in which are adjustably mounted the journal bearings 3 and 5 for the shaft 2 carrying the rotors of the gang condenser, one end of the shaft having mounted thereon the usual drum or dial 7 provided with the customary scale markings or indicia.

The rotor of each condenser unit consists of a series of plates 10 rigidly secured to a sleeve 11, which is pinned to the shaft 2. The cooperating stator element or member 20 of each condenser comprises a series of plates 12 secured to a base 13, which, in turn, is fastened to the casing by means of a spring bracket 14. The plates or leaves of the stator and rotor are so disposed that the plates of the respective members alternate in various degrees of overlap, when the rotor is operated to bring the elements of the condenser into cooperative relation. The stator element of each condenser is not strictly static, 30 but is so constructed and arranged as to be susceptible of a limited range of movement toward and from the rotor. As stated, the stator is supported at one end by a spring bracket 14 and the other end of the stator is provided with an insulating post or foot 16 secured to the cross bar 15 of the stator, which post 16 rests on the short arm of a lever 17, which is pivoted on a shaft or rod 18 fixed to the ends of the casing 1, the longer arm of the lever extending out through the slotted opening in the front of the casing. The several levers 17, which are associated with the separate condensers, are spaced on the shaft or supporting rod 18 by means of sleeves 19, so that said levers are retained in proper relation to engage the insulating posts 16 upon which the ends of the respective stators rest.

From the foregoing description, it will be apparent that moving the free ends of the levers 17 manually will effect the movement of the corresponding stators into greater or lesser overlapping relation with the coacting rotors and therefore vary the capacities of the respective condensers.

In making adjustment for a given dial setting (as, for example 650 kilocycles, as indicated in Fig. 13), the operator manipulates the three levers 17, moving them up and down until a maximum response is secured. The usual procedure will be to progress with the corrective adjustment of the levers from the antenna circuit to the detector circuit usually from left to right, the operation preferably being performed twice in rotation, due to the

slight retroactive mutual tuning action of the circuits. This adjustment of the several condensers is somewhat analogous to a "vernier" adjustment in its effect, but, in the present case, when once made, it is permanent for a given setting, that is to say, if the tuning dial is turned to some other setting and subsequently turned back to the reading of the first setting, the sub-circuits will be in perfect accord. In other words, when the several levers 70 17 have been adjusted to move the stators of the several condensers to effect the desired compensating capacity adjustment of the respective condensers, further manipulation of the levers in the ordinary operation of the set 75 80 will not be necessary, until and unless some change in the constants of the set make a readjustment of the stator elements necessary or desirable.

A manual adjustment of the several condensers by operation of the levers 17 while effective for a given dial setting, would not be similarly effective for another and different dial setting, wherefore, in order to insure the proper correctional adjustments of the stators of the several condensers throughout the range of the dial setting, the apparatus is provided with special means for automatically effecting the correctional adjustments of the several stators by the corresponding levers, which are operated by adjustable cams rotatable with the rotors, the desired adjustment of the cams being effected by the initial manual adjustment of the stators by their operating levers. To this end, there is associated with each of the condensers a face plate or disk 30, which is fixed to the sleeve 11 of the corresponding rotor and, therefore, rotates simultaneously with the rotor. Each disk or face plate 30 is provided with a series of radial slots 31, in each of which is slidably mounted a runner or support, the several runners serving to hold an adjustable cam 40 in its various positions of adjustment. Said cam comprises a flexible strip of metal, 95 which is locked to the face plate against movement in a longitudinal direction and also in a direction normal to the surface of the face plate or disk, but is capable of being adjusted radially with respect to the disk in whole or in part. Each of the runners includes a body portion 32 engaging a corresponding slot 31 in the disk with oppositely disposed ears 33, 33 engaging the face of the disk, a looped spring 34 serving to secure the runner to the disk with a frictional force sufficient to prevent displacement of the runner, except by engagement with positively actuated means. Each of the runners, except those at the end and the middle of the series, is provided with an open slot 35 in which the cam strip 40 is engaged, as more particularly illustrated in Fig. 8. Each of the end runners is provided with a slot 35' closed at its top, which prevents movement of the cam 100 105 110 115 120 125 130

in a direction normal to the surface of the disk 30, as illustrated in Fig. 9. The middle runner is provided with two hook-like extensions 30a, 30a overlying the slot 35, which extensions engage a slot or opening 41 in the mid section of the cam 40, thereby preventing any movement of the cam in the direction of its length.

As stated, a disk or face plate 30 is associated with each of the rotors and moves therewith in its various adjustments. Each of the levers 17 is provided with a slotted ear or lug 20, which is in straddling engagement with the corresponding cam 40, so that, when a given lever 17 is moved up or down to effect the proper correctional adjustment of the stator with respect to the rotor, the corresponding cam 40 is simultaneously adjusted locally in a radial direction with respect to the disk by the manual movement of the engaging lever and this adjustment of the cam will be maintained by the springs 34, which lock the runners in frictional engagement with the disk 30. This adjustment of the cam for a given setting of the condenser and the correctional adjustment of the stator thereof by the lever 17 will insure the reproduction of the correctional adjustment, when the same setting is repeated, by the cam moving the lever to the same extent that it was moved initially in the manual correctional adjustment.

It will be seen, therefore, that by moving the free ends of the levers up and down, the cam 40 is changed in shape simultaneously as the capacity of the corresponding condenser is adjustably altered, so that, when the cams of the three condensers are rotated in changing the dial setting, they simultaneously move their respective levers and stators to the same extent that the latter were moved by the manual actuation of the levers, thereby securing the proper correctional adjustment of each stator at the corresponding setting.

As indicated in Fig. 13, the levers 17 project through slots in the cabinet or casing of the radio receiving set so as to be readily accessible, and, in order to avoid accidental displacement of the levers, the projecting ends thereof may be shielded by a flap or closure 50 hinged to the front of the cabinet, as illustrated in Fig. 14.

The disposition and arrangement of the multi-stage condenser in a conventional circuit of a radio receiving set is illustrated in Fig. 15.

Although the invention has been described with particular reference to the initial manual correctional adjustments of the stator elements by means of the levers 17, which latter also set or adjust the cams to effect the subsequent correctional adjustments automatically, by the cams acting through the levers to move the stators, it will be apparent that the cams 40 may be adjusted manually,

in the first instance, to effect the correctional movements of the stators relatively to the rotors, the operative connections between the cams and the stators involving levers, such as 17, or any similar means.

What I claim is:

1. A variable condenser including more than one operator by the movement of any one of which operators the capacity of said condenser is varied, an adjustable cam associated with one of said operators, a follower for said cam associated with another of said operators and by which the shape of said cam is changed when said other operator is moved independently.

2. A variable condenser including an operator by the movement of which the capacity of said condenser is varied and including also a supplementary operator movable both co-ordinately with and independently of said first operator by the movement of which the capacity of said condenser is varied, a mechanical coupling between said first operator and said second operator by which said second operator is moved as a function of the movement of said first operator, and means associated with said coupling by which said coupling is changed to change said function when said second operator is moved independently of said first operator.

3. A variable condenser including rotor and stator members, a lever for initially adjusting the stator relatively to the rotor, an adjustable cam movable simultaneously with the motor, and connections between the lever and the cam whereby the movements of the lever to effect the initial adjustment of the stator will set the cam to effect the selective adjustment automatically.

4. A variable plate condenser, comprising a rotor member, an adjustable cam fixed thereto, a stator member mounted for limited movement relative to the rotor, manually operated means for moving the stator to initially effect compensating capacity adjustments between the rotor and stator, and connections between the cam and the manually operated means to set the cam to effect the subsequent capacity adjustments automatically.

5. A variable condenser, comprising a rotor including separate leaves fixed to a rotary shaft, a stator including leaves adapted for interposition with respect to the rotor leaves, a pivoted lever engaging the stator leaves for manually adjusting the latter relatively to the rotor leaves, a disk fixed to the rotor shaft, an adjustable cam track mounted on said disk including a resilient strip carried by runners slidable in radial slots in said disk, and a slotted lug on said lever straddling the strip; whereby the movements of the lever effects the initial capacity adjustment of the condenser and sets the cam, and subsequent dial setting of the condenser causes the cam to

move the lever to effect the same capacity adjustment.

6. A gang of plate condensers each comprising a rotor mounted on a common shaft and a stator mounted for limited movement relatively to the rotor to effect compensating capacity adjustments, a lever for manually adjusting each stator, an adjustable cam for each condenser fixed to said shaft, and connections between the several levers and the corresponding cams; whereby the movements of the levers to effect initial adjustment of the condensers will set the cams to repeat the adjustments through the levers upon subsequent dial settings of the condensers.

7. In a radio circuit including sub-circuits, each sub-circuit tuned by means of a variable condenser, a common operator for coordinate-
20 ly moving all of said condensers to different capacity settings, an auxiliary operator for each condenser to vary the capacity of each condenser independently of the other condensers to achieve capacity adjustments at each common setting, an adjustable cam for each condenser, and setting means for each of said cams actuated by the independent movement of the corresponding auxiliary operator and operated by said cams to move said auxiliary operators when said common operator is moved, whereby the capacity of said condenser is returned to the adjusted value at a subsequent identical common setting.

8. Tuning apparatus for radio circuits including means to change the frequency of said circuit, an adjustable cam, an engaging member operatively coupling said cam with said frequency changing means to change the frequency of said circuit as said cam is moved relatively to said engaging member, said en-
35 gaging member also engaging said cam to adjust said cam when said engaging member is moved independently of said cam.

9. Tuning apparatus control for radio circuits including means to change the frequency of said circuit, a movable support, an adjustable cam comprising a flexible member frictionally engaged by said support, an engaging member for operatively coupling said flexible member with said frequency changing means
45 to change the frequency of said circuit as said cam with its support is moved independently of said engaging member, said engaging member also engaging said flexible member to move the latter with respect to said support
50 to a different stable position of adjustment when said engaging member is moved independently of said cam.

10. A variable condenser including an operator to change said condenser to different capacity settings, an adjustable cam movable coordinate-
60 ly with said operator, auxiliary means to vary the capacity of said condenser, a cam engaging member operatively connected with said auxiliary capacity varying means
65 whereby said capacity varying means

is actuated to correct the capacity of said condenser at different capacity settings, said cam engaging member also acting to change the shape of said cam to adjust said cam.

In testimony whereof I affix my signature. 70
NOEL DEISCH.
